CLAIM

I claim the ornamental design for an arcade game prize, as shown and described.

DESCRIPTION

FIG. 1 is a perspective view of an arcade game prize showing my new design;

FIG. 2 is a top plan view thereof;

FIG. 3 is a side elevational view thereof; and,

FIG. 4 is a front perspective view of an arcade game prize in an arcade game cabinet.

All broken lines in the drawings depict environmental structure for the arcade game prize that form no part of the claimed design.
